REDUCTION OF METALLIC BODIES

Abram P. Steckel and Howard S. Lamb, Youngstown, Ohio, assignors to The Cold Metal Process Company, Youngstown, Ohio, a corporation of Ohio

Application May 4, 1931, Serial No. 535,030

28 Claims. (Cl. 80—32)

This invention relates to the reduction of metallic bodies and is particularly directed to the problem of gauging the amount of reduction. It is herein described as applied to the cold rolling of strip metal in a mill of the type illustrated in my Patent No. 1,744,018, dated January 14, 1930, although it is applicable to the reduction of other metal bodies, for example, wire.

A wide variety of proposals have been made for the solution of the problem of gauging the thickness of metal as it issues from a reducing means, such as a cold rolling mill. None of them have proved satisfactory. When the metal is travelling at high speed it is difficult or impossible to directly measure its thickness with accuracy despite the refinements which may be imposed in the measuring device. Various electrical circuits, usually employing amplifying tubes, and supposedly responsive to variations in the thickness 20 of the metal have also been proposed, but these have not proved satisfactory in service.

We have found that the problem may be solved in a highly desirable fashion by an indirect process of measurement which involves the measurement of the rate of elongation. In all metal rolling, with the possible exception of the rolling of ingots wherein there are blow-holes to be closed off, the volume of the metallic body under treatment is considered to be constant. Therefore the 30 cross sectional area multiplied by the length is a constant and, assuming the width to remain constant, the elongation is a measure of the reduction. While in certain classes of rolling and in certain types of mills the metal widens during 35 rolling, it is not inevitable that widening occur. On the contrary, as shown by Patent No. 1,744,018, the widening may be eliminated by using work rolls of sufficiently small diameter. We provide for measuring the elongation of the material as 40 a means for determining the amount of reduction. This is particularly accurate in a mill where no widening occurs, but even if some widening does take place, the method will be sufficiently accurate for such classes of product as are therefore produced.

We prefer to measure the entering and delivery speeds of the material preferably by driving members such as sheaves or pulleys from the metal itself. We have employed the invention in connection with a cold rolling mill, such as illustrated in Patent No. 1,744,018, wherein the material is pulled back and forth by means of reels through a pass consisting of small work rolls backed by larger rolls having anti-friction mounting. The 55 material in its passage from one reel to another is carried around cooling sheaves which properly align the material with the roll pass. These sheaves may be conveniently employed in carrying out the present invention. We prefer to drive 60 discs or wheels from such shafts, the discs or

wheels being connected to an indicator, one disc tending to move the indicator in one direction, the other tending to move it in the opposite direction. In a present preferred form the invention employs a pair of coaxial discs with an indicator freely rotatable therebetween. The indicator has a roller bearing against each disc. The discs are driven by the entering and the delivered material, with compensation made in the driving connection of one of the discs exactly to 70 compensate for the inevitable difference in speed of the entering and delivered material. This compensation is such that with a desired amount of reduction the discs are traveling in opposite directions at the same speed. Hence if the reduction actually being achieved is exactly equal to that which is desired, the indicator will remain stationary. However, even a slight departure from the desired amount of reduction will cause a movement of the indicator. The device is particularly delicate because the effect of an improper rate of reduction is cumulative on the indicator and, since the movement of the indicator is in effect a measurement of the increase in length of the material, much more positive and accurate results can be attained than where attempting to measure thicknesses direct, because the length dimension is on an order of magnitude much greater than the thickness.

Provision is made for varying the amount of reduction in accordance with the showing of the indicator. The connection may, if desired, be automatic, but for ordinary circumstances it may be manual.

While the invention, as above stated, is preferably embodied in the structure above briefly outlined, the essential principles may be employed in various forms. As an example, an electric current may be employed, the amount of current being proportioned to the relative speed of the entering and delivered material. This, however, while satisfactory for some purposes, is not as perfect as the embodiment above outlined, for the electrical effect obtained may be due to an error of a given size if the mill is delivering material at 1000 feet per minute, or it may be due to an error say twice as great if the mill is delivering material at 500 feet per minute. In short, such form of the invention gives a result which involves the absolute speed of the material which is not so in the preferred form. In certain cases, too, the speed of the rolls may be employed as bearing a relationship to the delivered speed of the material. Ordinarily, however, I prefer to apply direct measuring devices to the material after issuance from the mill.

In the accompanying drawings illustrating a present preferred embodiment of the invention, Figure 1 is a side elevation of a mill having the measuring device applied thereto; and

Figure 2 is a top plan view, largely diagrammatic, showing certain operating parts of the mill of Figure 1.

The mill illustrated in Figure 1 comprises a housing 2 having reels 3 and 4 adapted to be driven from a common power source, not shown, and to be employed alternately for reeling and paying out the material. The connection of the reels with the power source is controlled by a lever 5. Material being fed from, say, the reel 3 passes over a cooling sheave 6 and thence past wipers 7 and a guide 8 through work rolls 9. The work rolls are small undriven rolls which are backed by large diameter rolls 10 mounted in anti-friction bearings 11. The issuing material passes over a cooling sheave 12 and thence to the reel 4. The upper backing roll 10 is adjustable vertically. Its bearings are carried in cases 13 slidable in the housing and supported by spring balance mechanism 14. Wedges 15, adjustable laterally by hand wheels 16 and 17, determine the spacing of the work rolls 9 from one another.

The cooling sheave 6 is provided with a shaft extension 18 to which is secured a cone pulley 19, and the cooling sheave 12 is provided with a shaft extension 20 to which is secured a cone pulley 21. The shaft extension 18 also carries a loose cone pulley 22 and between the opposed faces 23 and 24 of the pulleys 19 and 22 there is arranged a spider 25 having rollers 26 which engage such faces. The spider 25 also carries pointers 27 cooperating with a graduated arc 28 which is held in place by brackets 29 secured to the housing 2 of the mill.

35 The pulleys 21 and 22 are connected by a crossed belt 30, which belt is preferably a fine but strong cord or thread, such as silk fish line. The pulleys are made very light in weight so as to have a minimum of inertia effect. The belt 40 is kept taut by a belt tightener 31.

The shaft extension 20 also carries a pulley 32 which is loose thereon like the pulley 22 and is connected to the pulley 19 by means of a crossed belt 33. The pulleys 21 and 32 are provided with 45 a spider 25 having a cooperating scale 28, as above described. It is intended that the pointer at one side of the mill shall be used when the mill is being operated in one direction, and that the pointer at the other side shall be used when 50 it is operating in the other direction.

The proper amount of friction between the faces of the cone pulleys and the pulleys 26 on the spiders is obtained by compression spring 34 backed by collars 35 on the shaft extensions 18 55 and 20, the compression springs acting through anti-friction thrust bearings 36 to press the tight and loose pulleys together.

Now assume that material is being fed from the reel 3 to the reel 4, and that a certain reduction, say, for example, a 10 percent reduction, is desired. The steps of the cone pulleys are so arranged that the belts may be fitted into different grooves on the pulleys so that the pulley 32 will run faster than the pulley 19 in amounts corresponding to different desired percentages of reduction. In the case just given, if it is a 10 percent reduction in thickness (and no variation in width) there will be a corresponding and definite elongation. Therefore, the cooling sheave 12 70 will run faster than the cooling sheave 6 in a definite ratio. The belt 33 will therefore be placed in such grooves of the pulleys 19 and 32 as will speed up the pulley 32 to give it the same number of revolutions per minute as the pulley 21 75 makes. However, by reason of the fact that the

belt 33 is crossed, the pulleys 21 and 32 will be rotated in opposite directions. If the amount of reduction is exactly that desired, the peripheral speed of each of the pulleys 21 and 32 at the point where it engages the rolls 26 will be the same, and therefore the rollers 26 will rotate but their axes will not be moved around the pointer 27 but will stand stationary. If, however, there is even a slight deviation from the desired percentage, the pointer will begin to move in one direction or the other, depending upon whether the reduction is greater or less than that which has been determined upon. Consequently, an adjustment of the pass must be made, as by adjusting the screw-downs.

While material is being fed from the reel 3 to the reel 4, the indicator at the right-hand side of the mill will be employed to check the reduction. It will not, however, be necessary to disconnect the indicator at the left-hand side. The pointer 27 of this indicator will simply rotate but will be disregarded. When the mill is driven in the reverse direction the belt 30 will be placed in the proper pulley steps corresponding to the desired percentage of reduction, and the indicator at the left-hand side of the mill will be utilized.

We have illustrated and described a present preferred embodiment of the invention and have indicated certain modifications thereof. It will be understood, however, that this is by way of illustration only, and that the invention may be otherwise embodied or practiced within the scope of the following claims.

We claim:

1. In the method of gauging the reduction of a metallic body, the step consisting in measuring its rate of elongation during reduction.
2. In the method of gauging a metallic body, the steps consisting in measuring its rate of elongation during reduction, and varying the amount of reduction in accordance therewith.
3. In the method of reducing a metallic body, the steps consisting in passing the material through a reducing means, and measuring the rate of elongation while the material is still engaged by the reducing means.
4. In the method of rolling strip material, the steps consisting in passing a strip to be reduced through a mill and measuring the rate of elongation of the material while it is in the mill.
5. In the method of reducing a metallic body, the steps consisting in passing the same through a reducing means, driving a member in accordance with the entering speed of the material, driving a member in accordance with the delivery speed thereof, and comparing the speeds of such members.
6. In the method of reducing a metallic body, the steps consisting in passing the same through a reducing means, driving a member in accordance with the entering speed of the material, driving a member in accordance with the delivery speed thereof, and controlling the reduction of the body to maintain a determined ratio between such speeds.
7. In the method of reducing a metallic body, the steps consisting in passing the same through a reducing means, driving a member in accordance with the entering speed of the material, driving a member in accordance with the delivery speed thereof, and varying the setting of the reducing means in accordance with the relative speeds of such members.
8. In the method of reducing a metallic body,

- the steps consisting in passing material back and forth through a mill, driving a member in accordance with the entering speed thereof on each pass, driving a member in accordance with the delivery speed thereof on each pass, and controlling the reduction of the body to maintain a determined ratio between such speeds. 80
9. In the method of reducing a metallic body, the steps consisting in passing it through a reducing means, driving a member in accordance with the entering speed of the material, driving a member in accordance with the delivery speed thereof, driving a third member from one of such driven members at a speed which bears relation to the speed of such driven member equivalent to a desired amount of reduction, and maintaining the speed of the third member and of the other driven member the same. 85
10. In combination with a metal reducing apparatus, means movable at rates corresponding to the entering and delivery speeds of the material being reduced, a member movable at a rate which bears a determined ratio to the speed of one of said movable means, and means for comparing the speed of said member with the other of said movable means. 90
11. In combination with a metal reducing apparatus, means movable at rates corresponding to the entering and delivery speeds of the material being reduced, a member movable at a rate which bears a determined ratio to the speed of one of said movable means, and means indicating when said member and the other of said movable means are moving at equal speeds. 95
12. In combination with a metal reducing apparatus, means movable at rates corresponding to the entering and delivery speeds of the material being reduced, a member movable at a speed related to the speed of the entering material, a member movable at a speed related to the speed of the delivered material, and means indicating variations in the ratio of the speeds of such members. 100
13. In combination with a rolling mill for reducing metal, sheaves driven by the entering and the delivered metal, and means for comparing the speeds of the sheaves. 105
14. In combination with a metal reducing apparatus, a member movable at a speed related to the speed of the entering material, a member movable at a speed related to the speed of the delivered material, an indicator, and connections with each of said members, one member tending to move the indicator in one direction and the other tending to move it in the other direction. 110
15. In combination with a metal reducing apparatus, a rotatable member driven at a speed related to the speed of the entering metal, a rotatable member driven at a speed related to the speed of the delivered metal, and means actuatable by both of said rotatable members, one tending to move the same in one direction, and the other tending to move it in the other direction. 115
16. In combination with a metal reducing means, a disc driven at a speed related to the speed of the entering material, a disc driven at a speed related to the speed of the delivered material, an arm between the discs, and a pulley on the arm engaging a face of each disc. 120
17. In combination with a metal reducing means, a disc driven at a speed related to the speed of the entering material, a disc driven at 125
- a speed related to the speed of the delivered material, an arm between the discs, a pulley on the arm engaging a face of each disc, and means for varying the ratio between the speed of one of said discs and the speed of that portion of the metal to which the disc speed is related. 130
18. In combination with a rolling mill having reducing rolls and sheaves on each side about which the material passes, said sheaves being driven by the material, and means for comparing the relative speeds of the sheaves. 135
19. In combination with a rolling mill having work rolls and backing rolls of larger diameter, the work rolls being sufficiently small to inhibit widening of the material being rolled, means for measuring the rate of elongation of the metal. 140
20. In the method of rolling strip metal, the steps consisting in passing the metal through rolls sufficiently small in diameter to inhibit widening of the material, and measuring the rate of elongation of the metal. 145
21. The combination with metal reducing apparatus, of means for measuring the speed of travel of material entering said apparatus, means for measuring the speed of material issuing therefrom, and means for comparing said speeds. 150
22. The combination with metal reducing apparatus, of means for comparing the speed of material entering the apparatus with the speed of the material issuing therefrom, and means for indicating variations in the ratio between said speeds. 155
23. The combination with metal reducing apparatus, of means for comparing the speed of travel of material entering the apparatus with the speed of travel of the material issuing therefrom, and means for indicating variations in the ratios of such speeds, said indicating means being effective to show the direction of said variations. 160
24. In the method of reducing a metallic body, the steps consisting in passing the body through a reducing means, measuring its entering and delivery speeds, and maintaining a predetermined ratio between said speeds. 165
25. The combination with a metal reducing apparatus, of means for comparing the length of the entering material with the length of the issuing material, and means for indicating the results of the comparison. 170
26. The combination with a metal reducing apparatus, of means for measuring the speed of travel of material entering the apparatus, means for measuring the speed of travel of material issuing from said apparatus, and means for comparing said measured speeds. 175
27. In an apparatus for gauging the reduction of metal lengths in a metal working device, a pair of rotatable members, means for driving said members respectively at speeds proportional to the speeds of the metal entering and leaving said device, and means for indicating a departure of the ratio of the speeds of said members from a predetermined value. 180
28. Apparatus for gauging the reduction of strip in a rolling mill comprising a shaft driven by the material entering the mill, a shaft driven by the material leaving the mill, a differential drive jointly actuated by said shafts, and an indicator actuated by said drive. 185
